(No Model.)

P. RIESECK.
STAIRWAY.

No. 412,898.

Patented Oct. 15, 1889.

UNITED STATES PATENT OFFICE.

PETER RIESECK, OF ALLEGHENY, PENNSYLVANIA.

STAIRWAY.

SPECIFICATION forming part of Letters Patent No. 412,898, dated October 15, 1889.

Application filed June 13, 1887. Serial No. 241,222. (No model.)

To all whom it may concern:

Be it known that I, PETER RIESECK, a citizen of the United States, residing at Allegheny, in the county of Allegheny and State 5 of Pennsylvania, have invented certain new and useful Improvements in Stairways; and I do hereby declare the following to be a full, clear, and exact description of the invention, such as will enable others skilled in the art to 10 which it pertains to make and use the same, reference being had to the accompanying drawings, which form a part of this specification.

My invention relates to an improvement in 15 stairways, and has for its object a means for accommodating and facilitating the descent of a large number of persons. This I accomplish by constructing two separate and independent stairways about a suitably-constructed central column, in a manner that 20 will be fully described hereinafter.

In the accompanying drawings, Figure 1 is 25 a side elevation of a portion of my improved stairway constructed in accordance with my invention. Fig. 2 is a continuation of the same. Fig. 3 is a plan view taken on the line $x-x$, Fig. 1. Fig. 4 is a plan view of the top landing.

To put my invention into practice, I employ 30 a supporting-column, which in the present instance I have shown as consisting of four uprights a , which are placed equidistant from one another in the form of a square. From the base of this column I construct a stairway b upward to a platform c and provided 35 with an inner d and outer hand-rail e , which, by means of properly-constructed balusters f , support the outer extremity of the treads. The inner hand-rails are bent around and 40 secured to the columns, so as to form additional supports to the flights of stairs. From this platform c the stairway b is continued upward along the rear of the columns a to a similar platform c' ; thence upward along the opposite 45 side of the starting-point to the platform c^2 . From this platform the stairway is continued upward along the front of the columns a to the platform c^3 and from this point to the balcony g , attached to the wall of the 50 building. In a structure of but two stories in height this stairway b ends at the first. I

now commence a similar stairway h on the opposite side of the columns a , the entrance of which is in an opposite direction to that before described. This stairway h is continued upward about the columns a , from one landing i to the other or next above, until the second balcony g' or story is reached.

In order to avoid the danger of obstructing the stairways at the base, I arrange the entrances or exits of the two stairways at the base of the column at opposite ends of the same diagonal of the column; or, in other words, the entrance or exit of the stairway h at the base of the column is at one end of a diagonal line 65 indicated by the dotted line y in Fig. 3, while the corresponding entrance or exit of the other stairway b at the base of the column is at the opposite end of said diagonal. (See Fig. 3.) By thus arranging the entrances or 70 exits of the two stairways at the base of the column the persons beginning the ascent or descent of one of the stairways will not interfere with or obstruct the persons at the base of the other stairway. It will also be 75 noted that the two stairways are entirely separate and independent, that they wind around the common supporting-column in the same direction, and that the landings of said stairways are at widely-separated points, 80 whereby the danger of a crush or jam of the persons occupying the two stairways is avoided.

If the building is of three stories, the first-described stairway b is continued from the 85 first landing to the third, which in case of a fire would serve to empty the first and third floors while the other is being used by the second. If constructed for a four or more story building, the two stairways b and h land alternately—as, for example, in a seven-story building the first-described stairway b lands at the first, third, fifth, and seventh stories, and the other h at the second, fourth, and sixth stories.

It will be seen by reference to Figs. 1 and 2 of the drawings that the two stairways are entirely separate and independent and wind in a series of flights at right angles to each other and in the same direction about the columns a , and having platforms at each angle.

Having thus described my invention, I do

not confine myself to the peculiar construction of the stairways, as the same may be built in a number of different ways; but

What I claim, and desire to secure by Letters 5 Patent, is—

1. In a stairway, the combination, with the supporting-columns, of two sets of stairs composed of flights arranged at right angles to each other around the columns and provided 10 with platforms at the angles, substantially as specified.

2. The combination, in a stairway, of the supporting-columns, the flights extending around the columns and arranged at right 15 angles to each other, and the platforms located at the angles of the flights, the upper platforms of each flight being arranged to connect with

different stories of a building, substantially as specified.

3. The combination, in a stairway, of the 20 supporting-columns, the independent stairways located on opposite sides of the columns and consisting of a series of flights at right angles to each other, and a series of platforms at the angles of the flights, the flights and 25 platforms being provided with hand-rails and balusters, the inner hand-rail being bent around and secured to the columns, substantially as specified.

PETER RIESECK.
